Primary Examiner — Susan E Krakower(74) *Attorney, Agent, or Firm* — Klarquist Sparkman, LLP**CLAIM**

(57) The ornamental design for a rebounder skirt, as shown and described.

DESCRIPTION

FIG. 1 is an oblique view of a first embodiment of a rebounder skirt, as viewed from above and one side.

FIG. 2 is a front elevation view of the rebounder skirt of FIG. 1, the rear elevation view being identical thereto.

FIG. 3 is an oblique view of a second embodiment of a rebounder skirt, as viewed from above and one side; and, FIG. 4 is a front elevation view of the rebounder skirt of FIG. 3, the rear elevation view being identical thereto.

The broken lines showing a rebounder frame and matt illustrate environmental structure which forms no part of the claimed design.
